UNITED STATES PATENT OFFICE

134,064

DESIGN FOR A MINIATURE SHRINE

Erwin Herz, New York, N. Y.

Application July 30, 1942, Serial No. 107,762

Term of patent 3½ years

To all whom it may concern:

Be it known that I, Erwin Herz, without nationality, residing at 321 West 94th Street, New York city, in the county of New York and State of New York, have invented a new, original, and ornamental Design for a Miniature Shrine, of which the following is a specification, reference being had to the accompanying drawing, forming part thereof.

Fig. 1 is a front elevation and

Fig. 2 is a vertical sectional view taken on line 2—2 of Fig. 1 of a miniature shrine embodying my new design.

I claim:

The ornamental design for a miniature shrine, as shown.

ERWIN HERZ.
